(57) **CLAIM**

I claim the ornamental design for a fragrance bottle, as shown and described.

DESCRIPTION

The patent or application file contains at least one drawing executed in color. Copies of this patent or patent application publication with the color drawing(s) will be provided by the Office upon request and payment of the necessary fee.

FIG. 1 is a front view of a first embodiment of a fragrance bottle, according to my design;

FIG. 2 is a rear view of the fragrance bottle of FIG. 1;

FIG. 3 is a right side view of the fragrance bottle of FIG. 1;

FIG. 4 is a left side view of the fragrance bottle of FIG. 1;

FIG. 5 is a top view of the fragrance bottle of FIG. 1;

FIG. 6 is a bottom view of the fragrance bottle of FIG. 1;

FIG. 7 is a front view of a second embodiment of a fragrance bottle, according to my design;

FIG. 8 is a rear view of the fragrance bottle of FIG. 7;

FIG. 9 is a right side view of the fragrance bottle of FIG. 7;

FIG. 10 is a left side view of the fragrance bottle of FIG. 7;

FIG. 11 is a top view of the fragrance bottle of FIG. 7; and,

FIG. 12 is a bottom view of the fragrance bottle of FIG. 7.
